CLAIM

The ornamental design for a male scrotum support, as shown and described.

DESCRIPTION

FIG. 1 is a front elevational view of a male scrotum support, showing my new design;

FIG. 2 is a side elevational view thereof;

FIG. 3 is a top plan view thereof;

FIG. 4 is a bottom plan view thereof;

FIG. 5 is a perspective view thereof, in use position, the broken line showing is for illustrative purposes only and forms no part of the claimed design;

FIG. 6 is a rear elevational view thereof; and

FIG. 7 is a side elevational view thereof, opposite that shown in FIG. 2.
